CANISTER VACUUM CLEANER

Stephen K. Lauderback, Elmhurst, Ill., assignor to
Sunbeam Corporation, Chicago, Ill.

Filed July 5, 1973, Ser. No. 376,771

Term of patent 14 years

Int. Cl. D15—05

U.S. Cl. D7—166

FIG. 1 is a perspective view of a canister vacuum cleaner embodying my new design;

FIG. 2 is a top plan view thereof;

FIG. 3 is a side elevational view thereof, with the opposite side view being a mirror image thereof except for the protruding electrical cord plug which is shown in FIGS. 1, 2, 4 and 5;

FIG. 4 is a front elevational view thereof; and

FIG. 5 is a rear elevational view thereof.

I claim:

The ornamental design for a canister vacuum cleaner, as shown and described.
